(57) **CLAIM**

The ornamental design for a holder for a blood pressure device, as shown and described.

DESCRIPTION

FIG. 1 is a perspective view of a holder for a blood pressure device embodying our new design;

FIG. 2 is another perspective view thereof;

FIG. 3 is top view thereof;

FIG. 4 is bottom view thereof;

FIG. 5 is a side view thereof;

FIG. 6 is another side view thereof;

FIG. 7 is a front view thereof;

FIG. 8 is a rear view thereof; and,

FIG. 9 is another perspective view thereof.

Broken lines, where shown, are used to illustrate portions of the holder for a blood pressure device or environmental subject matter that form no part of the claimed design.
